UNITED STATES PATENT OFFICE.

WILSON W. CAREY, OF LOWELL, MASSACHUSETTS.

PULLEY.

SPECIFICATION forming part of Letters Patent No. 322,898, dated July 28, 1885.

Application filed December 11, 1884. (No model.)

To all whom it may concern:

Be it known that I, WILSON W. CAREY, a citizen of the United States, residing at Lowell, in the county of Middlesex and State 5 of Massachusetts, have invented certain new and useful Improvements in Pulleys; and I do hereby declare that the same are fully described in the following specification and illustrated in the accompanying drawings.

10 This invention relates to improvements in pulleys; and it is carried out as follows, reference being had to the accompanying drawings, where—

Figure 1 represents a side elevation of the 15 improved pulley, and Fig. 2 represents a cross-section of the same. Fig. 3 represents a detail view of the pulley-hub.

Similar letters refer to similar parts wherever they occur on the drawings.

20 *a* is the rim of the pulley, as usual, made of wood or metal, as may be desired, and to the inside of said rim are secured, by means of suitable screws or bolts, the metal shoes *b b*, each one having a radial perforation, *b' b'*, for 25 the reception of the outer end of one of the pulley-arms *c*, as shown in Figs. 1 and 2. The outer end of each arm *c*, is screw-threaded, and passes loosely through the perforation *b' b'* in its shoe *b*, but is provided on the inside of 30 the latter with a pressure-nut, *d*, and set-nut *d'*, the latter being provided with the annular cup or shell *d''* in its inner end, so as to conceal and protect the inner end of the screw-threaded portion of the arm *c*, by which arrangement a very neat and workmanlike appearance is given to the connecting place between each arm *c* and its nuts and shoe, as 35 well as a proper protection obtained for the screw-threaded part of the arms, by which such 40 screw-threaded portions are prevented from accidental injury and defacement.

e represents the shaft, to which the hub is secured by means of a key or set-screws. The hub is made in two parts, *ff*, each forming, 45 as it were, an annular shell properly fitted on the shaft *e*. Each hub part *f*, has in its inner end a flange, *f'*, and on the abutting sides of such flanges are made the radial grooves or recesses *f'' f''*, for the reception of the inner ends of the respective arms *c c*. On each 50 flange *f'*, between the outside of shaft *e* and the inner end of each arm *c*, is left a projection or step, *f''*, as shown in Fig. 2, against which the inner end of the respective arms *c c* 55 rest. The flanges *f' f'* are firmly clamped

against opposite sides of the respective arms *c c* by means of the screw-bolts *g g*, passing through holes in said flanges, and provided with nuts *g' g'*, as shown in the drawings. The arms *c c* are made of steel, and by making them of such a material I obtain great strength of the pulley, combined with lightness, as compared with pulleys of ordinary construction in which cast or wrought iron arms are employed. The steel arms *c c*, being lighter and more rigid than wrought-iron arms, have also the property of being somewhat elastic, so that the pulley will return to its normal condition after it has been exposed to any undue strain sidewise. The hub *ff* is centered relative to the rim *a* by turning the pressure-nuts *d d*, and thereby pressing and securing the steel arms *c c* between their respective shoes *b b* and steps or projections *f'' f''* in the bottom of the grooves *f'' f''* 75 in the hub-flanges *f' f'*.

If so desired, I may modify the construction of the hub by making the sleeves *ff* in one single piece with one of the flanges *f'*, and making the other flange loose around the hub 80 and bolt it to the first-named flange, with the steel bars *c c* between them, by means of screw-bolts, as above described.

Having thus fully described the nature, construction, and operation of my invention, 85 I wish to secure by Letters Patent and claim—

1. The central hub, *ff*, with recessed flanges *f' f'' f''*, as described, combined with the radial steel arms *c c*, the pressure and holding nuts *d d'*, and outer rim, *a*, as and for the purpose set forth.

2. In a pulley, the outer rim, *a*, and screw-threaded steel arms *c c*, combined with pressure-nut *d* and check-nut *d'*, having cup-protector *d''* in its inner end, as and for the purpose set forth.

3. In a pulley, the divided hubs *ff*, having grooves or radial recesses *f'' f''* in the flanges *f' f'*, for the reception of the inner ends of the radial metal arms *c c*, such arms being clamped between said grooved flanges by means of screw bolts and nuts *g g'*, as and for the purpose set forth.

In testimony whereof I have affixed my signature in presence of two witnesses.

WILSON W. CAREY.
